LOCK.

1,228,109.

Specification of Letters Patent. Patented May 29, 1917.

Application filed February 18, 1914. Serial No. 819,578.

To all whom it may concern:

Be it known that we, ANDRO GRUDOSKI and STANISLAW SZTONNHEWSKY, subject of the Emperor of Austria and subject of the Czar of Russia, respectively, residing at Horning, in the county of Allegheny and State of Pennsylvania, have invented certain new and useful Improvements in Locks, of which the following is a specification.

10 This invention relates to improvements in locks, and pertains more particularly to structures which do not depend entirely upon the intricacies of the key structure for the effectiveness of the lock against opening.

15 The object of the invention is to provide a structure of this type which is simple in construction, efficient in operation, and which can be manufactured at a relatively low cost.

20 To these and other ends, the nature of which will be readily understood as the invention is hereinafter disclosed, said invention consists in the improved construction and combination of parts hereinafter fully
25 described, illustrated in the accompanying drawings, and more particularly pointed out in the appended claims.

In the accompanying drawings, in which similar reference characters indicate similar parts in each of the views,

Figure 1 is a view partly in section and partly in plan of a lock constructed in accordance with this invention, one of the inclosing sections being omitted.

35 Fig. 2 is a cross sectional view taken on the line $x-x$ of Fig. 1, both sections of the lock casing being shown in reversed position.

Fig. 3 is a detail sectional view of a portion of the key.

As shown in the drawings, the lock casting is formed in two sections indicated at 4 and 5 respectively, these sections inclosing the operating parts of the lock. Section 4 may be considered as the base section, the parts being carried thereby, section 5 being in the nature of a removable cover for inclosing the parts.

Extending between the sections when assembled are a pair of pins 11, these pins being fixed in position and adapted to form guides for the member 32, said member

having a slot 33 through which these pins extend. As will be understood from Fig. 1, these pins act to permit member 32 to move in the direction of its length within fixed limits, the movements being confined to substantially a single plane. The member 32 is provided along one of its faces with a suitable number of hooked arms 35, these arms being adapted to engage keepers 13 carried by a latch plate 12, these keepers being adapted to enter and project through properly positioned openings or slots 10 formed in the laterally extending 65 wall 6 of section 4.

The keepers 13 and the hooked arms 35 are complementally formed to permit ready engagement and disengagement therebetween when the latch plate 12 is properly positioned with respect to wall 6, by the guided movement of member 32 permitted by pins 11, holding engagement being had between the keepers and hooked structure when the member 32 is at one extreme of its movement, these parts being disengaged when said member is at its opposite extreme of movement. Member 32 is normally held in position to provide such locking action by a spring 36 carried by section 4 and adapted to operate in connection with an end wall of member 32. 70 75 80

As will be readily understood, this arrangement provides a condition where member 32 is in position to provide locking action if keepers 13 are in complementary position, member 32 being retained in this position by reason of the action of spring 36. To change this condition, the following mechanism is employed. 90

40 designates an element mounted on a pin 39 carried by member 32, said element 40 being pivotally mounted and projecting laterally from member 32. Said element has a substantially straight face 44 adapted to contact with the free end of a spring 41, said spring tending to maintain the element in a predetermined position, partial pivotal movements of the element tending to change the length of contact between face 44 and spring 41, the spring restoring the normal contact relation when the element is free from restraint against such return movement. 95 100

Element 40 has its end opposite face 44 provided with a recess 45 and an extension or finger 46. As shown more particularly in Fig. 1, the recess 45 is located at one side of a plane extending at right angles to the direction of length of member 32 and passing through pin 39 in the direction of pin axis.

22 indicates a member between the sections 4 and 5 and adapted to receive the forward end of a key 29, the key having a bit 28, the key being insertible through the key-hole 31 in section 5, said key-hole, for purposes presently referred to, being located at a predetermined position, the position being such, however, that the key must be moved rotatively to bring the bit 28 into contact with element 40. Assuming the dotted line representation of bit 28 in Fig. 20 1 to be such entering position, pivotal movement of the key counter-clockwise will place the parts in position to move member 32 to its unlocking position.

Such counter-clockwise movement will bring bit 28 into contact with a lower face of element 40; since movement of member 32 in the direction which such counter-clockwise movement of the bit would provide is prevented by one of the pins 11, such contact 25 of bit and element 40 will cause member 40 to move on its pivot until the bit and element reach a point where this contacting face of element 40 passes out of contact with bit 28. During this movement, the 30 normal relation between spring 41 and face 44 is changed, so that when this pass-by relation is had between the bit and element 40, spring 41 will act to move element 40 to return it to its normal position, this 35 movement continuing until finger 46 contacts with bit 28, finger 46 projecting outwardly a distance sufficient to provide such contact when the remainder of element 40 passes out of contact with the bit. If, 40 when this point is reached, the counter-clockwise movement of the key be continued, element 40 will again be moved on the pivot until the bit passes out of contact with the finger, an operation which is ineffective to 45 provide any movement to member 32. If, however, the direction of movement of the key is changed to clockwise, when contact with bit and finger 46 takes place a radically different effect is produced, bit 28 entering in and contacting with the walls of recess 45, thereby attempting to return element 40 to its normal position by movement of the bit. However, the bottom of recess 50 45 is so located and the bit 28 has such length that when this return movement is attempted, a locking effect is produced between the bit and the walls of the recess, through the presence of the recess wall in the path of movement of the bit.

Since the point of such locking engagement is out of a plane which would intersect pin 39 and the axis of the key, a toggle effect is provided by the key and element 40, and since the distance between pin 39 and the bottom of recess 45 combined with the length of the bit 28 is greater than the distance between pin 39 and the key axis, the toggle cannot be straightened without breakage of parts except as relief may be provided by movement of one of the parts. In 55 the structure shown, this relief is had through the ability of pin 39 to move in the direction of length of the lock, this pin being connected to member 32, and member 32 being free to move in this direction of 60 relief, such movement of member 32 being against the tension of spring 36. As the pins 11 act to guide member 32 in a straight line, and since such straight line movement carries pin 39 in a similar direction, while 65 the outer end of bit 28 traverses the arc of a circle, it will be readily understood that if this movement of the member 32 be continued a distance sufficient to permit this 70 toggle to be straightened through increasing 75 the distance between pin 39 and the axis of the key, a point will be reached where the point of the bit passes to the opposite 80 side of the plane intersecting pin 39 and the key axis, whereupon, element 40 is rendered free to move pivotally in the opposite 85 direction and thus free bit 28 from restraint. When this latter action is had, spring 36 90 returns the member 32 to normal position.

The length of movement necessary to permit the straightening of the toggle in the manner indicated is sufficient to carry member 32 a distance which will free the hooked structures 35 from engagement with the keepers, thus unlocking the lock, the hooked structures then returning to locking position 100 through the return movement of member 32 under the action of spring 36.

On the contrary, if the key be initially 105 moved clockwise, the bit 28 will simply contact with the opposite surface of element 40 and move the latter pivotally until the end or point of the bit passes by the point of finger 46, whereupon, spring 41 will return element 40 to its normal position, there being no possibility of the formation of an 110 engagement between the element and the bit 28 which would be sufficient to counteract the pressure provided by spring 36 to retain the member 32 in its locking position.

115 From the above, it will be understood that the element 40 serves as a toggle joint member free to move pivotally under the action of the key in a continuous direction, but becoming effective as such member when the key bit is brought into a predetermined 120 relation to the element and then have its direction of movement reversed. Further-

more, this toggle joint element 40 does not in itself provide any indication when the predetermined relationship between the key bit and the element is had. For instance, 5 should reversal in the direction of movement of the key bit take place before element 40 has moved a distance sufficient to bring the end of the key bit into recess 45, this formation of the toggle joint will not be had and 10 no movement of member 32 would be produced. Similarly, if the initial movement of key bit 28 should carry it beyond the end of finger 46, a reversal in the direction of movement will be ineffective to move member 32. Consequently, the element 40 and 15 the bit 28 of the key form two toggle joint members adapted to be brought into joint relation by movements of the key a predetermined distance followed by a reversal in direction of movement of the key. In other words, these members establish the toggle joint effect solely upon the completion of a predetermined cycle of manipulations of 20 the joint members.

25 As a result, the difficulty of maliciously opening the lock is greatly increased, there being no mechanism by which any tell-tale effect would serve as a clue to enable an unauthorized person to readily provide the manipulation.

In the drawings we have shown the key as provided with a central opening 30 adapted to receive pin 27, thus aiding in properly positioning the key within member 22.

As will be readily understood, the particular formation of the outer end of the member 40 will control, to a great extent, the particular point where reverse movement of 40 bit 28 should be had, such configuration controlling the length of pivotal movement of element 40 under the initial action of the bit 28 before the toggle joint effect is produced by the reversal in movement of the 45 key.

We we claim is:—

1. In lock structures, a member carrying keeper-engaging means, a removable key, and an element carried by said member and 50 projecting into the path of movement of the key, said element having a pair of spaced projections differing in length and normally positioned in the path of travel of the key and either of which is brought 55 into contact with the key dependent on the direction of key travel, contact with one of the projections permitting the element to be movable under key manipulation to provide a toggle joint relation between the 60 key and element during a predetermined period in the movement of the key, the completion of the toggle joint providing a member-moving means effective to move the engaging means to disengaging position.

2. In lock structures, a member carrying 65 keeper-engaging means, a removable key, and an element pivotally carried by said member and projecting into the path of movement of the key, said element having a pair of projections differing in length 70 and an intermediate recess, said projections normally lying in the path of travel of the key, projection and key contact being limited to a single projection dependent upon the direction of key travel, with the 75 recess accessible to the key solely when said element has been moved pivotally in one direction, said element and the key having a toggle joint producing relation when the key extends into said recess, said relation 80 being completed solely by combined movement of the key and element in the reverse direction and being limited to a predetermined period in the length of key travel in such direction. 85

3. In lock structures, a member carrying keeper-engaging means, a removable key, an element pivotally carried by the member and extending into the travel path of the key, said element having a finger and 90 a projection differing in length and with an intermediate recess, said finger and projection being normally positioned to provide contact with either by the key during its travel, the selection of contact being dependent on the direction of travel, with the recess accessible to the key only when the element is moved in one direction by contact of key and projection, and means for moving the element to normal position and 100 retaining it in such position when the element is free from key restraint, said element and key being adapted to produce a toggle joint relation therebetween when the key extends into said recess, said finger acting to prevent movement of the element to normal position while the key extends into said recess, movements of the key and element in toggle relation removing the key 105 from such recess at the end of a predetermined period. 110

4. In a lock structure, a member carrying keeper-engaging means, means for limiting movements of said member to and from a normal position in a single lineal plane, 115 means for normally maintaining said member in its normal position, a pivoted element carried by said member and having a normal position, a spring coöoperating with said element to maintain it in such 120 normal position and return it thereto when moved out of such position, said element having a recess adapted to receive the ward of a key when in predetermined position, a removable key having a ward adapted to coöperate with said recess, said element and said key being normally located to permit ward and recess engagement at a predetermined 125 position.

mined point in travel of key and element,
said engagement providing a toggle joint
relation between the key and element when
movement of the key is reversed, movement
5 of the member under such toggle relation
tending to move the element to toggle
breaking position.
